UNITED STATES PATENT OFFICE.

THOMAS B. BOWMAN, OF CHICAGO, ILLINOIS, ASSIGNOR, BY MESNE ASSIGNMENTS, TO
ANCHOR COMPANY, A CORPORATION OF ILLINOIS.

RAIL-ANCHOR.

Specification of Letters Patent.

Patented Apr. 23, 1918.

1,263,368

Application filed January 11, 1915. Serial No. 1,640.

To all whom it may concern:

Be it known that I, THOMAS B. BOWMAN, a citizen of the United States, residing at Chicago, in the county of Cook and State 5 of Illinois, have invented new and useful Improvements in Rail-Anchors, of which the following is a full, clear, concise, and exact description, reference being had to the accompanying drawing, forming a part 10 of this specification.

This invention relates to improvements in rail anchors.

Railway rails and the like have a tendency to creep along the road-bed in the direction 15 of the traffic thereover. Various structures, known as rail anchors, have been devised for preventing this creepage. The problem has been to provide a simple, efficient anchor which may be readily manufactured, which 20 has a minimum weight, which may be easily and securely applied to a rail, and which will positively grip the rail and prevent it from creeping. To this end the present invention has been devised.

One of the objects of the invention is to provide an efficient anchor which will have a minimum weight.

Another object is to provide an improved anchor which will positively grip the rail 30 when it tends to creep.

Another object is to provide an anchor in which the means for attaching it to a rail is relieved of the creepage stress.

Another object is to provide an improved 35 anchor which will prevent creepage of a rail without causing injury to the roadbed.

A further object is to provide an anchor which may be easily and cheaply manufactured.

A further object is to provide an improved 40 anchor which may be readily applied to a rail.

Other objects and advantages of the invention will hereinafter appear.

In the accompanying drawings:

Figure 1 is a perspective view showing the inside of the anchor.

Fig. 2 is a side elevation of the anchor applied to a rail.

Fig. 3 is an end view and partial cross-

section showing the anchor attached to a rail.

Fig. 4 is a side elevation and partial cross-section showing the anchor gripping the rail.

The anchor which is shown to illustrate the invention has upper and lower jaws 1 and 2, a leg 3, a foot 4, and an arm 5, all of which are preferably integral and cast from malleable iron or steel.

The anchor is adapted to be applied to the side of a rail with the jaws embracing the rail base as shown in Figs. 2, 3 and 4, the upper jaw 1 being above and the lower jaw 2 below the base.

The leg 3 extends downwardly from the jaws and is provided with a foot 4 near its lower end adapted to engage a tie to act as a fulcrum on which the anchor may tilt. The engaging surface of the foot 4 is forward of the upper end of the leg so that the upper end is free to move after movement of the lower end is prevented by engagement of the foot 4 with the tie. The anchor is accordingly free to tilt with the foot 4 acting as a fulcrum.

The jaws 1 and 2 and the leg 3 form the main body of the anchor and are adapted to take the stress of creepage. A reinforcing web 10 preferably extends between the lower jaw 2 and the leg 3. The forward end of the upper jaw and the rear end of the lower jaw may be enlarged so as to give them increased strength where they impinge upon the rail base.

The arm 5 which extends upwardly from the jaws is adapted to be attached to the rail to carry the upper end of the anchor forward to tilt it. Any suitable means may be used for attaching the arm to the rail. An integral pin 6 is shown. The bifurcated end 7 of the pin may be spread or a cotter pin 8 may be inserted through the opening 9 to hold the pin in position. The pin not only serves to carry the upper end of the anchor forward with the rail but it also acts as a means for attaching the anchor to the rail.

When the rail tends to creep in the direction indicated by the arrow in Fig. 2, 100

the arm 5 causes the anchor to be carried along with the rail until the foot 4 of leg 3 engages a tie. Upon further tendency of the rail to creep the upper end of the anchor is moved forward but the lower end is retarded. The anchor is accordingly tilted on the fulcrum formed by foot 4 so that the forward end of jaw 1 impinges upon the top of the rail base and the rear end of jaw 2 impinges upon the bottom of the rail base. The base is thus firmly gripped between the jaws of the anchor. The more the rail tends to creep the tighter the jaws grip the base.

15 As soon as the jaws have gripped the rail base the attaching means 6 is relieved of the stress of creepage which is thereafter borne by the rail base, the jaws and the leg of the anchor. The attaching means 6 may therefore be comparatively small since it is subjected to very little strain. The reduction in size of the attaching means causes a corresponding reduction in the labor and cost of applying the anchor to a rail since the size 25 of the hole which must be drilled in the rail is reduced.

It will thus be seen that a simple and efficient rail anchor has been provided which will positively grip the rail when the rail 30 tends to creep. The means for attaching the anchor to the rail is relieved of the stress and strain of creepage and accordingly may be made of reduced size. This not only makes the anchor itself less expensive but it 35 also reduces the cost of applying the anchor to a rail since only a small hole need be drilled to receive the attaching means. This hole may be quickly and easily forced through the rail, the anchor slipped over the 40 side of the rail base and the attaching means applied after which the anchor needs no further attention. It will not fall off by reason of the jar of traffic or a reverse creepage. The attaching means may be slightly 45 loose and still the anchor will operate since it is only necessary that the attaching means hold the anchor in position on the rail so as to carry it forward to positively tilt it to cause the jaws to grip the rail base. Accordingly, a continuous inspection of the anchors 50 after they are in position for the purpose of determining whether they are tightly in engagement with the rail is not required. The anchor is fixed in one position relative to 55 the rail so that there can be no creepage by reason of the anchor slipping or sliding along the rail while not in actual gripping engagement therewith. The fact that the attaching means carries the upper end of the 60 anchor forward with the rail each time the rail starts to creep insures that the anchor is tilted to grip the rail. The action of the anchor is therefore positive. At the same time the rail is free to move relative to the 65 tie when the direction of traffic is reversed.

This prevents the tie being loosened in the roadbed.

In addition to the above-mentioned advantages, the anchor is simple and may therefore be easily manufactured. It may be 70 made in one integral casting, as shown, or, if desired, the attaching means may be made separately. The weight of the anchor is reduced to a minimum which is an important factor inasmuch as anchors are usually sold 75 by the pound or hundredweight. The anchor therefore combines the advantageous features of simplicity, low cost, inexpensive application and positive efficient operation.

It is manifest that various anchors may 80 be devised which will embody the invention set forth herein and that various modifications may be made in the structure which has been particularly set forth without in any way departing from the invention as defined by the claims appended hereto.

What I claim as new and desire to secure by United States Letters Patent is:

1. A rail anchor comprising a pair of jaws adapted to grip the base of a rail and having 90 their points of impingement with opposite sides of the rail base separated a relatively great distance in the direction of the length of the rail, a depending leg for engaging a cross-tie to tilt the jaws to cause 95 them to increasingly grip the rail as the rail tends to creep, and means projecting through the web of the rail to hold the anchor against displacement and insure positive tilting of the jaws.

2. A rail anchor comprising a pair of jaws adapted to grip between them the base flange of a rail, a depending leg to cause the jaws to increasingly grip the base when the leg abuts a tie as the rail tends to creep, a 105 strengthening web extending between said leg and jaws, and a pin cooperating with the web of the rail and about which the anchor can tilt to hold the anchor against displacement and to insure positive tilting when 110 the leg abuts a tie.

3. A rail anchor comprising a pair of jaws adapted to engage and increasingly grip the base of a rail when tilted, a strengthening web for each jaw, a depending leg for 115 abutting a tie to tilt the jaws as the rail tends to creep, a relatively thin strengthening web extending between the jaws and leg to prevent bending of the leg, and a pin extending through the web of the rail to hold 120 the anchor in place and positively insure the tilting of the jaws.

4. A rail anchor comprising a pair of jaws engaging the bottom and top surfaces of the rail base, a depending leg for tilting the 125 jaws to cause them to increasingly grip the rail when the leg abuts a tie as the rail tends to creep, a member extending upwardly from the jaws adjacent the web of the rail, a pin extending through said member and the rail 130

web to provide a pivot about which the jaws can tilt and to insure the tilting of the jaws when the leg abuts a tie, and a triangular strengthening web extending from the center of the leg to the jaws to prevent bending of the leg.

5 In witness whereof, I have hereunto sub-

scribed my name in the presence of two witnesses.

THOMAS B. BOWMAN.
